United States Patent Office

Des. 221,707
Patented Aug. 31, 1971

221,707

DISPOSABLE FORCEPS

Suel Grant Shannon, 3701 Sharon St.,
Harrisburg, Pa. 17111

Filed Jan. 19, 1970, Ser. No. 21,174

Term of patent 3½ years

Int. Cl. D24—03; D28—03

U.S. Cl. D83—12

FIG. 1 is a perspective view of medical forceps;
FIG. 2 is a side elevational view thereof;
FIG. 3 is a top plan view thereof;
FIG. 4 is a rear end view thereof; and
FIG. 5 is a front end view thereof.
I claim:
The ornamental design for disposable forceps, as shown.
